UNITED STATES PATENT OFFICE.

PHILIP H. FIELDING, OF EAST NORWALK, AND FREDERIC E. LEWIS, 2d, OF SAUGATUCK,
CONNECTICUT; SAID FIELDING ASSIGNOR TO SAID LEWIS.

VEHICLE-INDICATOR.

1,141,701.

Specification of Letters Patent. Patented June 1, 1915.

Application filed April 8, 1913. Serial No. 759,596.

To all whom it may concern:

Be it known that we, PHILIP H. FIELDING and FREDERIC E. LEWIS, 2d, citizens of the United States, residing at East Norwalk and Saugatuck, respectively, in the county of Fairfield and State of Connecticut, have invented certain new and useful Improvements in Vehicle-Indicators, of which the following is a full, clear, and exact description.

This invention relates to improvements in vehicle indicators.

The object of our invention is to indicate at the rear of a vehicle that the brakes have been applied and that the vehicle is slowing down, to warn the driver of a vehicle which is following closely in the rear thereof, of this fact, thus avoiding any opportunity for a rear-end collision.

Our invention relates to improved means for accomplishing this result, the construction of which will be more fully referred to and pointed out in the specification and claim appended hereto.

In the drawings, Figure 1 is an elevation of a vehicle showing the indicator in place; Fig. 2 is a central section of the indicator; Fig. 3 is a section on the line *a—a*, Fig. 2; Fig. 4 is a reduced end view of the indicator; and Fig. 5 is a diagrammatic view of the circuits.

The indicator comprises a cylindrical casing 1 provided with a front wall 2 having an opening 3 therein through which the insulated conductors lead into the interior of the casing. The rear wall 4 has an opening 5 in its upper surface which is substantially arc-shaped, and a circular opening in the center thereof having a flange 6 provided with screw-threads. A cap or cover 7 having coöperating screw-threads fits over said flange and carries a lens or other transparent closure which may be colored as desired, and through which the rays from a small electric incandescent lamp 8 are adapted to shine. This electric lamp is mounted on a socket 9 which is pivotally mounted by a loop of wire 10 closely surrounding said socket, the ends 11 of which are journaled in trunnions 12 mounted on a bar 13 of insulating material fastened to the rear wall. The socket is pivoted in this manner to allow it to be turned to a position where the axis of the lamp will be parallel with the

axis of the opening and so permit the lamp 55 to be removed when necessary through the opening. The bar 13 carries a contact 14 insulated from the frame and adapted to contact with the socket terminal 16.

Suitably mounted on the front wall is an electromagnet 17, the cores of which are provided with pins 18 adapted to support and guide the armature 19 which carries an arm 20 integral therewith and which is connected to a crank-shaft 21 supported on uprights 22 mounted on a cross-piece 23 connecting the front and rear walls of the casing. An arm 24 rigidly connected to the crank-shaft to move therewith, carries at its upper end a semicircular plate or banner 25 upon which is displayed the word "Slow", or some other appropriate word. The arm and indicating plate are normally biased to the dotted line position shown in Fig. 2, by the spring 26, and the armature 19 which is constrained to move with the arm 24, is thereby carried to a position away from the poles or cores of the electromagnet. The uprights which support the arm 24 are spaced from the rear wall of the casing in order to provide a space for the incandescent lamp and also to provide a space between the rear wall and the indicating plate which will be illuminated by the electric lamp when the indicating plate is in its perpendicular or indicating position. Attached also to the front wall by any suitable frame, is an electromagnetic bell 27 provided with a gong 28, which may be of any approved form. The circuit for the electromagnet passes through the contact 29 mounted on but insulated from the front wall of the casing. A sliding contact 30, mounted on the arm 24 or integral therewith, is provided with insulating sections 31 upon which the contact 29 rests when the arm is in either of its extreme positions, but which is adapted to complete the circuit through the electric bell while the arm is being moved from one extreme position to the other.

A circuit closer 32, which is of the well known type comprising two contacts 33 and 34 adapted to be bridged by the movable contact 35 is spring-pressed to circuit-closing position, but is held in open position by the engagement of the plunger 36 mounted on contact 35 with the brake-lever 37, while the brake-lever is in its normal position.

When, however, the brakes are applied, the brake-lever is moved out of engagement with the arm and the circuit is closed.

Referring to Fig. 5, which shows a diagrammatic view of the circuits, when the brake-lever is moved to apply the brakes, the normally open main circuit is closed at points 33, 34 and 35, and current will then pass through the parallel circuits 38 and 39 containing the electric lamp 8 and electromagnet 17, respectively, which circuits will remain closed as long as the brake is applied. The energization of the electromagnet will move the arm and indicating plate to its indicating position and the circuit 40 of the electric bell will be closed through contacts 29 and 30, which circuits will remain closed until the plate has reached its indicating position, at which point the circuit will again be broken by the contact 29 resting upon the second of the insulated sections 31, thus giving a momentary audible signal which will be sufficient to attract the attention of a driver of a vehicle approaching from the rear if he does not see the visual signal. The cutting of the electric bell out of circuit is desirable by the fact that the driver of a motor vehicle often holds the

brakes on for considerable periods, and after the alarm has once performed its function, its continued sounding would be objectionable on account of the consumption of current, and annoyance.

Having thus described our invention, we claim:—

In a vehicle indicator, a casing having openings in its rear face, an electric light in said casing opposite one of said openings, an indicator movable into and out of indicating position opposite the other of said openings, electromagnetic means for actuating said indicator, an electrically operated audible signal in said casing, parallel branch circuits for said lamp, indicator actuating means, and said signal respectively, a circuit adapted to be controlled by the vehicle brake common to said branch circuits, and a contact carried by said indicator located in the branch circuit of said audible signal.

In witness whereof, we subscribe our signatures, in the presence of two witnesses.

PHILIP H. FIELDING.

FREDERIC E. LEWIS, 2d.
